US0D1099109S

(12) **United States Design Patent** (10) Patent No.: **US D1,099,109 S**
P J (45) Date of Patent: ** Oct. 21, 2025

(54) **DISPLAY SCREEN OR PORTION THEREOF WITH GRAPHICAL USER INTERFACE**

(71) Applicant: **Salesforce, Inc.**, San Francisco, CA (US)

(72) Inventor: **Jose Lejin P J**, Bengaluru (IN)

(73) Assignee: **Salesforce, Inc.**, San Francisco, CA (US)

(**) Term: **15 Years**

(21) Appl. No.: **29/792,884**

(22) Filed: **Apr. 28, 2022**

(51) LOC (15) Cl. **14-04**

(52) U.S. Cl.

USPC **D14/485**

(57) **CLAIM**

The ornamental design for a display screen or portion thereof with graphical user interface as shown and described.

DESCRIPTION

FIG. 1 is a front view of a display screen or portion thereof with graphical user interface showing the claimed design; FIG. 2 is a second embodiment thereof; and, FIG. 3 is a third embodiment thereof.

The outer dot-dash broken lines in the figures show a display screen or portion thereof, and form no part of the claimed design. The other dot-dash broken lines in the figures show portions of the graphical user interface that form no part of the claimed design.

The dashed broken lines in the figures form part of the claimed design.

1 Claim, 3 Drawing Sheets
